UNITED STATES PATENT OFFICE.

ALFRED SAVILL TOMKINS, OF HOLMWOOD, CATERHAM, COUNTY OF SURREY,
ENGLAND.

PORTABLE COOKING-STOVE.

SPECIFICATION forming part of Letters Patent No. 400,271, dated March 26, 1889.

Application filed November 7, 1888. Serial No. 290,234. (No model.) Patented in England March 26, 1888, No. 4,623.

To all whom it may concern:

Be it known that I, ALFRED SAVILL TOMKINS, a citizen of England, captain in the Victoria Rifles, residing at Holmwood, Caterham, county of Surrey, England, have invented a new and useful Improvement in Portable Cooking-Stoves, (for which I have made application for Letters Patent in Great Britain, which patent when granted will bear date 26th 10 day of March, 1888, No. 4,623,) of which the following is a specification.

My invention relates to portable cooking apparatus especially suitable for military use or for travelers, as it can be used in the open 15 or with complete safety in a tent or on a wagon.

Figures 1 and 2 of the accompanying drawings are vertical sections on planes at right angles to one another, and Fig. 3 is a sectional plan of a cooking apparatus or camp-stove 20 according to my invention.

F is the fire-place, which can be supplied with fuel through the door O and down the inclined chute N, the draft being regulated by the ash-pit door S. The hot products of combustion ascend the central flue-space, C, from 25 which two side spaces, C' C', branch each way, and finally pass away by the chimney C². On each side of the fire F is a space, T, which can be used as an oven or for drying

materials placed in it. The space on each 30 side of the flue C is divided by horizontal partitions, so as to form four ovens, F', in which are placed cooking vessels or dishes B². On the upper part of the stove are placed boilers K. At the back and sides of the stove there 35 is a separate water-casing, R, which effectually protects from fire any combustible material in the neighborhood of the stove.

Having thus described the nature of this invention and the best means I know for carrying the same into practical effect, I claim—

A portable cooking apparatus consisting of a fire-place, F, flues C and C', chimney C², ovens F', and boilers K, in combination with the water-casing R, substantially as described. 45

In testimony whereof I have signed my name to this specification, in the presence of two subscribing witnesses, this 25th day of October, A. D. 1888.

ALFD. SAVILL TOMKINS.
